UNITED STATES PATENT OFFICE.

JOHN BYSTROM, OF CHICAGO, ILLINOIS.

LOOSE-LEAF BINDER.

1,270,246.

Specification of Letters Patent. Patented June 18, 1918.

Application filed October 9, 1916. Serial No. 124,552.

To all whom it may concern:

Be it known that I, JOHN BYSTROM, a citizen of the United States, residing at Chicago, in the county of Cook and State 5 of Illinois, have invented certain new and useful Improvements in Loose-Leaf Binders, of which the following is a description, reference being had to the accompanying drawings, forming a part of this specification, in which corresponding numerals of 10 reference in the different figures indicate like parts.

My invention relates to loose-leaf binders of the type having curved prongs attached 15 to opposite hinged binding members for engaging and holding perforated leaves, and my object is to provide a simple, cheap and effective locking means for detachably locking said binding members in operative holding 20 relation to each other, all of which is hereinafter more particularly described and definitely pointed out in the claim.

In the drawings—

Figure 1, is an end view of a loose-leaf 25 binder embodying the features of my invention as it would appear when closed, a portion of the cover members and leaves being broken away,

Fig. 2, is an interior view of the device as 30 it would appear when locked and the covers opened but without leaves, a portion of one of the hinged frame members being broken away, to show the manner in which the lock is engaged,

Fig. 3, is an end view of the device as it would appear when open and unlocked 35 ready for the insertion of leaves,

Fig. 4, is a transverse section taken upon the line 4, Fig. 2, viewed in the direction of 40 the arrow there shown, and

Fig. 5, is a section taken upon the line 5—5 Fig. 2, viewed as indicated by the arrows.

Referring to the drawings, 1 and 2 indicate 45 generally and as a whole the main frame members, which are formed from elongated sheet-metal plates bent at substantially right angles in cross-section as better shown in Fig. 4, to form counterpart or 50 complementary primary, secondary and flange portions 3, 4, 5, 6 and 7 and 8 respectively, the parts 3 and 4 being bent toward each other from the parts 5 and 6 respectively, and hinged together at 9, while the 55 flange parts 7 and 8 are bent in opposite

directions with respect to the parts 5 and 6, so that the part 7 will always be in a plane substantially parallel to that of the part 3, and the part 8 in a plane substantially parallel to that of the part 4. When, 60 therefore, the binder is closed the parts 3 and 6 will lie in a common plane, the parts 3 and 4 will abut against each other and the parts 7 and 8 will be parallel. As a result of this construction, the parts 5 and 6 65 will be spaced apart when the binder is open as shown in Figs. 3 and 4.

For the purpose of providing a suitable backing support for the binder, I attach 70 backing plates 10 and 11, to the parts 7 and 8, which plates are provided with flanges 12 and 13 respectively, bent at oblique angles thereto as shown in Fig. 4. The width of said flanges should be less than that of the parts 5 and 6 of the frame members and they should be so formed with respect to each other as to provide spaces 75 between the edges of said flanges as well as between said flanges and the axis 9 of the hinge. Said flanges serve as a support for 80 a continuous flexible binding 14 which spans the space between them in the manner shown at 15, Figs. 1, 3 and 4, and is extended in any well known way over hinged cover flaps 16 and 17. A plate 18, is rigidly attached by means of rivets 19 to the plates 7 and 10, and a like plate 20 to the plates 8 and 11, said plates serving as supports for the usual well known counterpart prongs 21 and 22 respectively, adapted to secure the 90 leaves 23 in place.

The ends of the parts 5 and 6 are bent at right angles to provide end flanges 23 and 24 respectively to close the spaces at the ends between the parts 5 and 12 and 6 and 13 respectively, so as to form a finish.

The following described locking mechanism is provided for securing the hinged frame members in locked relation to each other. A locking-member, generally designated by 25, is formed from sheet-metal and consists of integral portions 26 and 27, bent in cross-section at right angles to each other throughout its length. Said locking member is placed within the angle formed by the 100 intersection of the parts 4 and 6 and in parallel relation thereto, with the part or flange 26, against the part 4 and the part 27 against the part 6, in which relation said member is slidably held by means of clips 105 110

28, Figs. 2, 4 and 5, rigidly attached by means of rivets 29 to the part 6. One end of the part 27 is caused to project beyond the end of the frame plate and is provided 5 with a finger-piece or lug 30 bent at an angle thereto, by which it may be actuated. A coiled spring 31, Figs. 2 and 5, has one end attached to the part 24 and the other to a stud 32, upon said slideable locking 10 plates and serves to yieldingly hold said locking plate normally in a locking position. Slots 33, Figs. 2, 4 and 5, are formed in said locking-plate in position to register with hooked detents 34, which are rigidly attached 15 to the part 5, and curved, as shown in Fig. 4, so as to readily enter said slots. The slots 33 are in substantial registration with openings or slots 33^a Fig. 4, formed in the part 4. When the binding members are 20 brought together the hooks of the detents are brought into sliding angular engagement with the ends of the slots 33, thereby causing the spring to yield to permit their entry, when the recoil of the spring 25 stores the locking plate to a locking position. The binder may be unlocked by pressing against the lug 30 until the spring yields, when the binder may be opened as shown in Fig. 3. It is obvious that the mere closing

of the binding members will cause the lock- 30 ing members to snap into engagement.

Having thus described my invention, I claim:—

A loose-leaf binder comprising, in combination, counterpart longitudinal frame members having primary portions hinged together, said portions being arranged to abut against each other when the binder is closed, each of said primary portions having a secondary integral portion formed at right 40 angles thereto in cross-section, a longitudinally slideable locking member slidably held upon one of said secondary portions, said member consisting of an angle-bar adapted to fit in the angle formed by the intersection of said primary and secondary parts and having a slot therein for the reception of a detent, and a detent upon the other of said secondary portions for engaging said slideable locking member. 45

In testimony whereof, I have signed this specification in the presence of two subscribing witnesses, this 18th day of September, 1916.

JOHN BYSTROM.
